UNITED STATES PATENT OFFICE.

ROBERT MARVIN KELLY, OF LONGVIEW, TEXAS.

PLOW.

974,675.

Specification of Letters Patent.

Patented Nov. 1, 1910.

Application filed September 21, 1909. Serial No. 518,881.

To all whom it may concern:

Be it known that I, ROBERT M. KELLY, a citizen of the United States, residing at Longview, in the county of Gregg and State of Texas, have invented a new and useful Plow, of which the following is a specification.

The invention relates to improvements in plows.

10 The object of the present invention is to improve the construction of plows, more especially that shown and described in Patent No. 673,606, granted to G. A. Kelly, May 7, 1901, and to provide efficient means for assisting the bolt to hold the plow point in position and to prevent a vertical or upward movement of the point, when the bolt becomes loose through plowing.

20 A further object of the invention is to provide means adapted to interlock the landside plate or flange of the plow point with the nose of the standard, and arranged to coöperate with the interlocking means shown in the said patent for preventing the plow 25 points from swinging laterally toward the land when the bolt becomes loose.

With these and other objects in view, the invention consists in the construction and novel combination of parts hereinafter fully 30 described, illustrated in the accompanying drawing, and pointed out in the claims hereto appended; it being understood that various changes in the form, proportion, size and minor details of construction, within 35 the scope of the claims, may be resorted to without departing from the spirit or sacrificing any of the advantages of the invention.

In the drawing:—Figure 1 is a perspective view of the lower portion of the standard, constructed in accordance with this invention. Fig. 2 is a perspective view of the co-acting plow point or share in reverse position. Fig. 3 is a transverse sectional view. 45 Fig. 4 is a plan view.

Like numerals of reference designate corresponding parts in all the figures of the drawing.

In the accompanying drawing 10 designates the lower portion of the standard of a well known form of turning plow, and 11 designates the plow point or share. The form of these may be changed or modified as desired. The standard in the form shown 55 is provided with the usual upright landside

face 12 and the upper curved face 13, their meeting edges being indicated by 14. The plow point or share is secured upon the curved face 13 by means of a bolt 15, passing through registering perforations 16 and 17 of the plow point and the standard. Projecting from the lower portion of the curved face 13 and adjacent to the meeting edge 14 is an upstanding lug 18, the outer face of which forms a continuation of the 60 upright face 12. This lug, which is thickest at its lower end, tapers gradually toward its upper end until its upper face coincides with and merges into the upper face 13 of the standard. The lower end of the lug is 70 also inset slightly from the lower edge of the face 13, so that the said lower edge is continuous from one end to the other.

The plow point or share 11 comprises the usual working plate 19, having at one edge 75 the landside plate or flange 20 and on its underside a stop rib 21. The lower end of the standard fits snugly in the angle formed by the landside plate or flange 20 and the stop rib 21. Arranged in the underside of 80 the plow point between the landside plate or flange 20 and the stop rib 21 and contiguous to the said landside plate or flange is a notch or recess 22, which exactly corresponds to the shape of the lug 18. One of the walls of 85 the socket or recess 22 forms a continuation of the inner face of the landside flange 20. The standard is also provided at its upright landside face 12 with a lug 23, having its upper edge arranged substantially in the 90 plane of the curved upper face 13 of the standard, as clearly illustrated in Fig. 3 of the drawing. This lug 23, like the lug 18, is thicker at its lower or front end and tapers inwardly or rearwardly until its outer 95 face coincides with and merges into the outer upright face of the upright landside face 12 of the standard. The front end of the lug 23 terminates short of the front end of the nose of the standard. The landside 100 flange 20 is provided in its inner face with a longitudinal recess or socket 24, which corresponds exactly with the shape of the lug 23. One of the walls of the socket or recess 24 is arranged in the same plane and coincides with the lower face of the working plate 19 of the plow point.

The plow point is applied to the standard in the usual manner. The underside of the plow point bears directly upon the curved 110

face 18 of the standard, and the landside flange fits against the landside face 12. The standard will then fit snugly in the angle between the landside flange 20 and the stop rib 21. The openings 16 and 17 will also be in alinement, and the bolt 15 is passed through the same. The lugs 18 and 23 fit snugly in the sockets or recesses 22 and 24 and will be held therein by the bolt 15. The lug 18, as explained in the aforesaid patent, will prevent the plow point from swinging laterally toward the landside when the bolt is a little loose, and the lug 23 of the present invention by interlocking with the landside flange will prevent a vertical or upward movement of the plow point when the bolt gets loose from plowing. By interlocking the plow point with the standard to prevent both vertical and horizontal or lateral swinging, the fastening bolt is relieved of strain and the plow point is rigidly held in position, thereby greatly increasing the durability of the plow point and rendering the plow effective until the plow point is worn out. Also the rigid character of the attachment of the plow point greatly assists the plow in doing better work.

The face of the lug 23 inclines backwardly with respect to the upright landside face 12 of the standard, and the bottom of the recess 24 inclines forwardly with respect to the said inclined landside face 12, so that when the face of the lug fits against the bottom of the recess, the tendency will be to force the plow point in correct position against the mold board 25, and the landside flange 20 against the landside shoulder 26 and prevent the forward movement of the plow point. This will greatly assist the lug 23 in preventing the vertical movement of the plow point for the closer the plow point is held against the mold board and the flange against the landside shoulder, the more snug will the lug fit in the recess and hold the point rigid.

Having thus fully described my invention; what I claim as new and desire to secure by Letters Patent, is:—

1. In a plow, a standard provided in its lower portion at a point remote from the landside with a bolt opening and having its landside face provided with a lateral projection of less area than said face and having its front end extending in advance of the bolt opening, a share having its landside flange fitted against the landside face of the standard and provided in its face with an interiorly arranged socket receiving the said projection, whereby the share is held against upward movement on the landside face, said share having an opening registering with the bolt opening of the standard; and a fastening device passed through the said openings.

2. In a plow, the combination of a stand-

ard having at a point remote from the landside a vertically disposed bolt opening in its lower portion, and provided at its landside face with a tapered lug projecting laterally from said face and having its front end extending in advance of the bolt opening, and a share having a face fitted against the landside face of the standard and provided with an interiorly arranged socket corresponding in shape to and receiving said lug, whereby the share is locked against upward movement on the landside face by wedging the share on the standard, said share having an opening registering with the opening of the standard, and a fastening device arranged in the said openings and securing the share to the standard.

3. In a plow, the combination of a standard having at a point remote from the landside a vertically disposed bolt opening in its lower portion, and provided at its landside face with a shoulder, and having a tapered lug projecting laterally from the landside face and of less area than said face, said lug having its front end extending in advance of the bolt opening and having its thicker and narrower end at the front and spaced from the front of the standard and decreasing in thickness and increasing in width toward its rear end and merging into the landside face at a point in advance of the said shoulder, a share having its landside flange fitted against the said shoulder and provided in the inner face of the said flange with a socket of correspondingly tapered shape as 100 and receiving the lug of the standard to hold the share against upward movement on the landside face by wedging the share on the standard, said share having an opening registering with the opening of the standard, and a fastening device arranged in the said openings and securing the share to the standard.

4. In a plow, the combination of a standard provided with lugs projecting from its upper and landside faces, and a share having corresponding recesses in its lower face and in the inner face of its landside flange, said lugs fitting snugly in the recesses, whereby the share is locked against both vertical and horizontal movement.

5. In a plow, the combination of a standard provided with tapering longitudinal lugs projecting from the upper and landside faces of the standard, and a plow point provided in its lower face with a tapering recess and having a landside flange provided also in its inner face with a tapering recess, said recesses snugly receiving the tapered lugs, whereby the plow point is 125 interlocked with the standard and held against both vertical and horizontal movement.

6. In a plow, the combination with a mold board, of a standard having a landside face 130

and provided with a shoulder at the rear end thereof, said standard being also provided at the said face with a tapering lug, and a plow point provided with a landside flange having a tapering recess to receive the lug, the face of the lug being inclined backwardly and the bottom of the recess being inclined forwardly, whereby the plow point will be caused to fit tightly against the mold

board and the landside shoulder and in proper position with relation to the same.

In testimony, that I claim the foregoing as my own, I have hereto affixed my signature in the presence of two witnesses.

ROBERT MARVIN KELLY.
